UNITED STATES PATENT OFFICE.

GEORGE P. BRAND, OF NEW YORK, N. Y.

FLANGE-CONTROLLING MECHANISM.

1,193,352.

Specification of Letters Patent. Patented Aug. 1, 1916.

Application filed April 13, 1915. Serial No. 21,164.

To all whom it may concern:

Be it known that I, GEORGE P. BRAND, a citizen of the United States, residing at New York, in the county of New York and State 5 of New York, have invented certain new and useful Improvements in Flange-Controlling Mechanism, of which the following is a specification.

This invention relates to certain new and 10 useful improvements in means for automatically controlling the flanges of a take-up spool in automatic musical instruments and the like, said means being controlled by the note sheet and thus rendering the spool 15 applicable for note sheets of different widths. The mechanism which controls the flanges serves to set the latter or retain them in fixed position after once adjusted to the width of sheet, and may be controlled from 20 the note sheet in a variety of ways.

One of the objects of the invention is to provide centralizing means and pneumatically controlled music openings or ports in combination with the automatic adjustable 25 flanges, thereby accurately delivering the music on the take-up spool and holding it always in tact after being delivered. In devices of this character employing fixed flanges it has been necessary to space such 30 flanges a sufficient distance apart to take in the greatest width of sheet, usually allowing a little space so that the edges of the sheet do not contact with the flanges. Having too much room for the music sheet on 35 the take-up spool between the flanges on large rolls of music causes bad re-winding and inaccurate results because it wanders from side to side and makes it wind loose and the core will shift back and forth. The 40 sheet is thus wound unevenly and the one edge will at times engage the one flange and then the other edge will engage the other flange. The disadvantageous results will be readily understood. Furthermore, where 45 tracking devices are employed in conjunction with take-up spools having fixed flanges this uneven winding throws a great deal more work on the tracking device and distorts the music and, consequently, unsatisfactory results are attained. My present 50 invention overcomes these objections. Furthermore, my present improvement insures satisfactory results.

In conjunction with the movable flange I 55 employ automatically movable sheet controlled means operating in unison therewith.

In the present instance, I have chosen to show such sheet controlled means in the form of movably mounted ports or openings controlled by the music sheet and in turn 60 controlling the movable flanges, but it is to be understood that this is but one form of sheet controlled means that may be employed in connection with the movable flanges hereinbefore described. I may also 65 employ in conjunction with the note sheet controlled and controlling devices hereinbefore referred to, means for moving the music spool in conjunction with said aforesigned devices, although this latter may 70 sometimes be omitted.

Other objects and advantages of the invention will hereinafter appear and the novel features thereof will be particularly pointed out in the appended claims.

75

The invention is clearly illustrated in the accompanying drawings, which, with the numerals of reference marked thereon, form a part of this specification, and in which—

Figure 1 is a front elevation of my present improvement. Fig. 2 is a rear elevation of the lower portion thereof showing the various pneumatic connections. Fig. 3 is a top plan with the top of the music box and other portions removed. Fig. 4 is a vertical 80 section from front to rear, as on the line 4—4 of Fig. 1, looking in the direction of the arrows. Fig. 5 is a bottom plan. Fig. 6 is a sectional view of the music spool actuating pneumatics. Fig. 7 is a plan of the valve 85 chest.

Like numerals of reference indicate like parts throughout the different views.

In the accompanying drawings I have shown only such parts of a mechanical musical instrument as pertain directly to the present invention, it being understood that the parts not shown or described may be of any conventional or approved form and connected and arranged to operate in the 95 usual manner.

In these drawings, 1 is the music box, 2 the tracker, 3 the take-up spool, 4 the music spool, 5 the spindles of the latter and 6 a perforated note sheet, all of well known 100 construction. The flanges 7 of the take-up spool are movable in the direction of the length of the shaft 8. They are designed to be moved inward simultaneously toward each other by the following means. At each 105 end of the music spool box, in the present instance shown as at the bottom thereof

110

where they are out of the way and can be excluded from dust, etc., I affix a pneumatic 10, and each pneumatic carries upon its movable leaf, a rod or the like 11 which 5 extends upward through a slot in the partition or bottom board 12 of the spool box, as seen best in Fig. 4. The member 11 may be secured in any suitable manner to its pneumatic, one convenient form being shown in 10 Fig. 4. The upper end of each member 11 extends preferably above the shaft 8 of the take-up spool so as to exert its influence at a point above said shaft upon a member 13 which extends downward through a slot 14 15 in the member 12, as clearly seen in Fig. 4, and is, intermediate its ends, sleeved upon the shaft 8 so as to move freely thereon and to engage against the hub 15 of the adjacent flange 7, as seen in Fig. 1. This member 13 20 is connected at its upper end in any suitable manner with means carrying a movable port or opening 16 shown in this instance as movable in an elongated slot 17 near the end of the trackerbar, it being understood that 25 there is one of these carried by each member 13 and, consequently, one near each end of the trackerbar, as seen in Fig. 1. These ports are controlled by the margin or surface of the note sheet, as will hereinafter appear. 30 Each of these ports 16 is connected by flexible tube or the like 18 with a passage 19 in the coupling block 20, which passage leads through the passage 21 and the tube or the like 22 to a diaphragm chamber 23, or 35 24, see Figs. 6 and 7, of which 25, see Fig. 6, is one of the diaphragms.

26 is a valve chamber, one for each diaphragm chamber, see Fig. 6.

27 is a communication between the tension 40 chamber 28 and the valve chamber 26.

29 is a port or opening leading from the valve chamber 26 to the atmosphere as do the ports 33 and 34.

30 and 31 are valves controlling the ports 45 or passages 27 and 29 respectively, as seen clearly in Fig. 6, said valves being carried by a common stem 32 guided in any suitable manner.

35 and 36 are pneumatics having their 50 movable boards or members connected by a rod 37 so that they move in unison. These pneumatics are affixed upon opposite sides of the valve chest 38, and in the fixed member of each pneumatic is a passage 39 which 55 communicates with a passage 40 in the valve block and this, in turn, by means of a passage 41 with a passage 42 which, in turn, communicates by passage 43 with the valve chamber 26, all as clearly shown in Fig. 6.

60 Tubes 44 connect with the passages 42 and 43 and with the pneumatics 10, as seen clearly in Fig. 2. Between each passage 41 and the passage 42 there is a restriction 45, as seen in Fig. 6, to retard the inflation and 65 deflation of the pneumatics 35 and 36.

46 is a tube affording communication between the exhaust mechanism (not shown) and the tension chamber 28, as seen in Figs. 2 and 6. The two tension chambers 28 are connected by a passage 47 shown in Fig. 6. 70 The members 13 are extended in opposite directions toward each other, as seen in Fig. 3, and their adjacent ends are pivotally connected, as at 48 and 49, with opposite ends of a lever 50 pivoted between its ends, as 75 at 51, so that the flanges 7 will be moved in unison.

The pneumatic 35 has connected thereto one end of a rod 52, the other end of which is pivotally connected, as at 53, with the 80 lower end of the vertical bar 54 pivotally mounted between its ends, as at 55, on a lateral support 56 extending from the end of the box 1, as seen in Fig. 1. To the upper end of the bar 54 is pivotally connected, as 85 at 57, a rod or link 58, the outer end of which is adjustably connected, as at 59, with the depending portion 60 of a U-shaped member 61, the other depending member 62 of which supports one end of the shaft 63 90 95 which carries the sprocket wheel 64 of the drive mechanism.

65 is another U-shaped member rigidly secured to the member 61 to move therewith, and in one depending member 66 the shaft 95 63 is supported while in the other depending portion 67 the left hand spindle is mounted, as seen in Fig. 1.

68 are uprights having at their upper ends pins or the like 69 loosely engaged in the 100 adjacent portion of the U-shaped member 65, being mounted at their lower ends so as to have the necessary oscillatory movement to allow the U-shaped members to move with the greatest freedom.

With the parts constructed and arranged substantially as hereinbefore described, the operation, briefly stated, is as follows:— Fig. 1 shows the parts in position for starting to play. The roll is in position and upon drawing the note sheet over the tracker bar and fastening it to the take-up spool in the usual manner and starting to play, the ports 16 and the flanges 7 being outside the edge of the sheet, tension is supplied to the tension chambers 28, and air enters into the diaphragm chambers 32 through the ports 16 and connections, lifting the valves 30, 31 shutting off the atmosphere, causing the pneumatics 10 on each side of the box to partially collapse, carrying the flanges 7 toward the note sheet and the ports 16 also toward the note sheet until one or both are practically covered thereby or sufficiently covered, thereby bringing the note sheet central, to cause the valves 30 and 31 to return to the position in which they are shown in Fig. 6. The springs 100, acting on the flanges 7 against the pressure of the pneumatics, have a tendency to force 115 120 125 130

the ports 16 outward, which causes fluctuation of the valves 30 and 31. If the note sheet starts to move to the right or left, say to the right, to a slight degree, the flanges 7 being against opposite edges of the sheet, the ports 16 will remain stationary and the valve corresponding to the right hand port will be in its normal position, as shown in Fig. 6, and the valve corresponding to the left hand port will be in the reverse position. Consequently, the pneumatic 35 will start to collapse, bringing the sheet back to its central position. During the lateral movements of the sheet, the flanges are held stationary by the pneumatics 10; hence the flanges are not caused to leave the edges of the sheet, as one or the other of the pneumatics 10 is always under tension. Likewise, this holding of the flanges serves to minimize the movement of the ports 16, thereby practically giving fixed ports to accommodate any width of sheet, and at the same time minimizing the lateral deviation of the sheet, as the ports 16 are automatically self-adjusting to the closest relation to the sheet. The flanges and the ports 16 move together under all conditions. While in the present structure I have provision for the ports 16 being normally out beyond the edges of the sheet, a reversal of this effect may be produced and the holes or ports 16 normally inward so as to be under the margins of the sheet when it is first introduced into the machine, by reversing the pneumatics 10 so that they will tend to pull the flanges 7 outward instead of inward, and by reversing the valves so they will collapse the said pneumatics from beneath the sheet, to move the ports outward. It is to be understood that in this arrangement the flanges will normally be of a lesser distance apart than the width of the sheet, but will be moved outward to accommodate the sheet before the edges thereof reach said flanges, the ports having by this time moved outward to their first inoperative position, assuming the same position as do the ports in the construction hereinbefore described, ready to assume their duties as control openings for keeping the sheet in central position and holding the flanges in close relation with the sheet.

It will be seen that with the flanges and ports controlled so as to automatically adjust themselves to the most accurate relation with the sheet, the said ports are in position to control sheet centralizing mechanism therefrom to keep the sheet practically absolutely central, with practically no deviations whatsoever, it being imperceptible to the eye.

I have shown one form of transmission mechanism and its operating pneumatics for use in connection with the flange controlling mechanism and the ports 16 and their con-

nections, but it is to be understood that this form is herein illustrated merely for the purpose of making clear the connection between the post-operative devices and the music spool, but it is to be understood that the invention is in no wise restricted to this particular construction and connection of the transmission mechanism.

Modifications in details may be resorted to without departing from the spirit of the invention or sacrificing any of its advantages.

What is claimed as new and useful is:—

1. A take-up spool with relatively movable flanges, and means under control of the surface of a note sheet for moving said flanges.

2. In a device of the character described, a take-up spool having movable flanges, pneumatic means for moving the flanges, and means controlled by the surface of a note sheet for causing the pneumatic means to move said flanges.

3. A take-up spool with relatively movable flanges and pneumatic means under control of the surface of a note sheet for moving said flanges.

4. A spool having movable flanges, means under control of the surface of a note sheet, and pneumatic means and connections whereby said flanges and note sheet controlled means are actuated simultaneously.

5. A spool having movable flanges, means under control of the surface of a note sheet, and pneumatic means and connections whereby said flanges and note sheet controlled means are actuated simultaneously in opposite directions.

6. In a device of the character described, movable flanges automatically movable, and means under control of the surface of a note sheet for moving said flanges.

7. In a device of the character described, movable flanges automatically controlled by the surface of a note sheet to accommodate sheets of different widths.

8. In a device of the character stated, a spool having movable flanges, means under control of the surface of a note sheet for moving said flanges, said means and flanges being movable in unison.

9. In a device of the character stated, a spool having movable flanges, means under control of the surface of a note sheet for moving said flanges, said means and flanges being movable in unison, and pneumatics operatively connected with and acting in unison therewith.

10. A take-up spool with relatively movable flanges, and means under control of the surface of a note sheet for moving said flanges, said flanges being held in close relation with the sheet.

11. In a device of the character described, a spool having relatively movable flanges

and movable means under control of the surface of a note sheet for moving said flanges.

12. In a device of the character described, 5 a take-up spool having movable flanges and movable sheet controlled means, said flanges and means being under control of the surface of a note sheet and automatically adjustable to the most accurate relation with 10 the sheet.

13. In a device of the character described, 15 a take-up spool having movable flanges and movable sheet controlled means, said flanges and means under control of the surface of a note sheet and being automatically adjustable to the most accurate relation with 20 the sheet, and sheet centralizing mechanism controlled thereby.

14. A take-up spool having relatively 25 movable flanges, an endwise movable music spool, and means controlled by the surface of a note sheet for controlling said flanges and music spool.

15. A take-up spool having relatively 30 movable flanges, an endwise movable music spool, and movable means controlled by the surface of a note sheet for controlling said flanges and music spool.

16. A take-up spool having movable 35 flanges, an endwise movable music spool, and means controlled by the surface of a note sheet for controlling said flanges and music spool, said flanges and means being movable in unison.

17. A take-up spool having movable 40 flanges, an endwise movable music spool, and movable means controlled by the surface of a note sheet for controlling said flanges and music spool, said flanges and means being movable in unison.

18. In a device of the character described, 45 a take-up spool having movable flanges, movable means under control of the surface of a note sheet for moving said flanges, pneumatic connections for moving said 50 means and flanges in unison, and a centralizing device in coöperative relation therewith.

19. A take-up spool with endwise movable 55 flanges, movable means under control of the surface of a note sheet and movable with said flanges, and pneumatic means controlled by said means and controlling said flanges.

20. A take-up spool with endwise movable 60 flanges, movable means under control of the surface of a note sheet and movable with said flanges, and pneumatic means controlled

by said means and controlling said flanges in one direction.

21. A take-up spool with endwise movable 65 flanges, movable means under control of the surface of a note sheet and movable with said flanges, pneumatic means controlled by said means and controlling said flanges in one direction, and means for moving said flanges in the opposite direction.

22. A take-up spool with endwise movable 70 flanges, movable means under control of the surface of a note sheet and movable with said flanges, pneumatic means controlled by said means and controlling said flanges, and a centralizing mechanism under the control of said movable means.

23. A take-up spool with endwise movable 75 flanges, movable means under control of the surface of a note sheet and movable with said flanges, pneumatic means controlled by said means and controlling said flanges in one direction, and a centralizing mechanism under the control of said movable means.

24. A take-up spool with endwise movable 80 flanges, movable means under control of the surface of a note sheet and movable with said flanges, pneumatic means controlled by said means and controlling said flanges in one direction, means for moving said flanges in the opposite direction, and a centralizing mechanism under the control of said movable means.

25. A spool with movable flanges, movable 90 means under control of the surface of a note sheet and movable with said flanges, and pneumatic means controlled by said means and movable in unison and also independently of each other.

26. A spool with automatically movable 95 flanges, and automatic note sheet centralizing means, both controlled by the surface of a note sheet.

27. A spool with movable flanges, mov- 100 able means at opposite sides of a note sheet controlled by the surface thereof for controlling said flanges, and a pneumatic for each of said movable means.

28. A spool with movable flanges, mov- 105 able means at opposite sides of a note sheet controlled by the surface thereof for controlling said flanges, and a pneumatic for each of said movable means, either of said pneumatics controlling said flanges and 110 means.

In testimony whereof I affix my signature.

GEORGE P. BRAND.
